UNITED STATES PATENT OFFICE.

CHARLES B. MOORE, OF EVANSTON, ILLINOIS, ASSIGNEE, BY MESNE ASSIGNMENTS,
TO AMERICAN ARCH COMPANY, OF NEW YORK, N. Y., A CORPORATION OF DELA-
WARE.

LOCOMOTIVE-BOILER FURNACE.

1,138,042.

Specification of Letters Patent.

Patented May 4, 1915.

Application filed December 18, 1911. Serial No. 666,350.

To all whom it may concern:

Be it known that I, CHARLES B. MOORE, a citizen of the United States, and a resident of the city of Evanston, county of Cook, and State of Illinois, have invented certain new and useful Improvements in Locomotive-Boiler Furnaces, of which the following is a specification.

My invention relates to improvements in locomotive boiler furnaces and has special reference to improvements in refractory baffles or walls, commonly called arches, for the fireboxes of locomotive boilers.

The general objects of my invention are to provide a refractory arch for installation and use in locomotive boiler fireboxes, of comparatively light weight and low cost; to provide an arch particularly adapted for installation in locomotive furnaces having inclined arch tubes and which shall find its support thereon; to provide an arch construction which will readily adapt itself to boilers of varying dimensions and arrangements of tubes; and parts of which can be readily removed to afford easy access to the side sheets for the repair of the stay bolts; and to provide an arch which, on account of its peculiar construction and arrangement of parts, will materially assist in the commingling and admixing of the firebox gases, to the end that substantially perfect combustion will be attained in the firebox.

A more special object of my invention is to provide a refractory arch structure which, while fulfilling the above general objects, will be especially adapted for installation and use in comparatively wide locomotive boilers and especially in such boilers which are equipped with two inclined arch tubes which are comparatively widely separated.

My invention consists in the assemblages of elements, combinations and relations of parts wherein and whereby the above objects are attained together with others hereinafter appearing, and all as hereinafter fully described with reference to the accompanying drawings, which form a part of this specification, and particularly and definitely pointed out in the appended claims.

In said drawings: Figure 1 is a central, vertical longitudinal sectional view of a locomotive firebox equipped with an arch illustrating one embodiment of my invention; Fig. 2 is a fragmentary horizontal sectional view of the firebox on the line 2—2 of

Fig. 1; Fig. 3 is a vertical transverse sectional view on the line 3—3 of Fig. 1; Fig. 4 is a detail transverse sectional view of the arch on the line 5—5 of Fig. 3; Fig. 5 is a detail transverse sectional view of the arch 60 on the line 6—6 of Fig. 3.

My invention is capable of embodiment in refractory arches of various details of construction and occupying different positions in the firebox and, although I have chosen 65 to confine the illustration of the invention to so-called front arches, it will be readily understood that my invention is not thus limited.

So-called front arches usually occupy an 70 inclined position at the front end of the firebox close to or in contact with the flue sheet and usually extend from side sheet to side sheet, and in fireboxes which are equipped with inclined circulating tubes find 75 their support thereon. The principal function of this form of arch is to deflect the firebox gases out of the direct path from the grate to the flues and cause them to zigzag back and forth through the firebox, not only 80 to retain them in the firebox a sufficient time for complete combustion to take place, but also to afford the effective even distribution of heat to the whole interior surface of the firebox, and especially throughout the whole 85 length of the crown sheet. The structures which embody my invention not only have the above important function, but they are preferably formed of individual bricks 90 which are so formed in themselves and assembled and related to each other that an arch is produced which is provided with diversely arranged and positioned gas deflecting surfaces and pockets or cavities 95 which materially assist in the thorough commingling and admixing of the firebox gases as they rise through the firebox. These various deflecting walls and surfaces also assist in the return to the fuel body of the more solid fuel particles and cinders. 100

As shown in the drawings, a locomotive firebox is formed of a flue sheet 2 at its forward end, a rear sheet 3 at its rear end connected by side sheets 4, 4, and a crown sheet 5. A grate 6 is provided at the lower end of 105 the firebox. Flues 7 lead forward from the flue sheet and the rear sheet is provided with a fire door or opening 8. The firebox itself is positioned within the shell 12 of the boiler. The firebox as illustrated is provided with 110

two circulating or arch tubes 9. As usual, these tubes extend from the lower portion of the flue sheet upwardly and rearwardly to the rear sheet and assist in the circulation of water between the front and rear legs of the boiler. The tubes 9, as shown in the drawings, are arranged quite close to the side sheets 4, only sufficient room being left between the tubes and the side sheets to permit 5 the convenient or proper placing of the firebox stay bolts. This arrangement of arch tubes, especially in boilers whose fireboxes are comparatively wide, produces a comparatively wide space, between the tubes, to 10 be covered or closed by the arch. It is desirable that arches for installation in such fireboxes shall be as light as possible consistent with the necessary strength and also 15 that they shall be so rigidly and securely held in position that they will permanently stay in place regardless of the severe jarring effect to which they are subjected.

In building my arches I use two main forms of bricks, limiting their sizes only by 20 the necessary features that they shall not be too heavy in themselves for convenient handling, nor so large that they cannot be readily passed through the fuel or fire door. These two forms of bricks comprise the arch 25 or span bricks *a* and the cover or roof bricks *b*. The span bricks *a* are adapted to be used in pairs to span the space between the tubes and they are formed to rest firmly on the tubes at their lower ends and abut together 30 at their upper ends. Each pair thus forms a span or arch 10 between the tubes and these bricks are formed to interlock at their abutting ends so that they are in a sense self-supported arches. These spans 10 are spaced 35 apart upon the tubes 9 and are held in spaced relation by means of the cover bricks *b* which find their support upon the spans 10 and in a practical sense close the spaces between these spans. I complete the arch by 40 closing the spaces between the tubes and the side sheets by means of bricks *c* somewhat similar to the cover bricks *b*, but formed especially for this purpose. It will be understood that the main part of the arch is in a 45 sense complete in itself formed up as it is of the spans 10 and the cover bricks *b*, and the side bricks *c* may or may not be used as may be desirable in the particular boiler in which the arch is installed.

50 The span bricks *a*, two of which form a span 10, are together longer than the space between the tubes 9 and hence when placed in position they occupy an inwardly and upwardly inclined position resting at their lower ends upon the tubes and at their upper ends against each other. Their lower ends are provided with grooves or sockets *a'* adapted to be firmly seated upon the tubes 9 and their upper ends are provided with interlocking tongues *a''* and grooves *a'''* which,

when the bricks are in position, prevent relative vertical movement of the abutting ends of the bricks, and hence retain them in interlocked condition.

It will be understood, of course, that the weight of the bricks holds them in their desired position. These bricks *a* are wide enough where they rest upon the tubes 9 to rest firmly thereon without rocking and I make these bricks deep enough to give them sufficient strength to carry their own weight and the weight of the superposed cover bricks *b*. I further form them with a number of gas deflecting pockets or cavities *a⁴* in their lower surfaces which lighten the bricks to a certain extent without detracting from their desired strength. I further form the lower or outer ends of the bricks *a* with grooves or gains *a⁵* upon their upper sides to receive the inner ends of the side bricks *c*. These bricks *c* are arranged in an upwardly inclined position resting at their inner ends upon the lower or outer ends of the bricks *a* and at their outer ends against the side sheets 4. These bricks *c* not only fill in the space between the main part of the arch and side sheets, but also act as locking bricks to assist in the maintaining of the arch against lateral movement in the firebox and thus remove some of the lateral strain of the weight of the arch from the tubes. The bricks *c* are preferably formed with an inner tongue *c'* which overlaps the lower end of the arch brick *a* and assists in making a gas tight joint between the two bricks. The spans 10 are held apart and the spaces between them are filled by the cover or roof bricks *b*. I usually prefer to arrange two of the cover bricks between corresponding span bricks, as shown in Figs. 1 to 3. These bricks are arranged between the upper edges of the span bricks and are provided upon their ends with flanges *b'* to enter complementary grooves *a⁶* in the edges of the span bricks *a*. This construction results in the upper or back surface of the arch being comparatively smooth whereby the cinders or ash which collect thereon are not retained but are caused to slide down off of the arch and be returned to the fuel body upon the grate.

It will be understood that the cover bricks might be plain slabs or plates and fulfil the function of filling the spaces between the span bricks and spacing them apart, but to more securely hold the spans in proper position, and for the purpose of providing the tops of the spaces between the spans with a plurality of smaller gas-mixing pockets and deflecting surfaces, I provide the lower surfaces of the cover bricks with longitudinally arranged ribs *b²* connected at their middle portion with transverse ribs *b³*. The ends of the ribs *b²* are arranged to abut the sides of the arch bricks and assist in maintaining them in position. This construction of the

cover bricks provides them with a plurality of small gas-mixing pockets b^4 in their under surfaces. It will be noted that regardless of the shape or form of the individual bricks of the arch the construction as herein outlined provides an arch with gas-deflecting surfaces arranged at various angles and also with gas-mixing pockets or cavities, side or locking bricks c are provided on their under side with cavities c^2 similar to the cavities in the other bricks which not only lighten these bricks but assist in the admixing of the fire-box gases. I prefer to form the outer ends of the bricks c with narrow central projections c^3 which not only assist in the convenient or easy fitting of the arch to the firebox, in that the narrow projections are more easily trimmed or broken than the whole width of the brick, but they also result in the side sheets being protected to only a slight extent from the heated firebox gases.

The installation of one of my arches in the firebox is a comparatively simple matter. I first place a span composed of a pair of the span bricks a upon the lower ends of the tubes 9 and space them from the flue sheet 2 by means of a spacing block or brick d . This brick d is arranged between the apex of the span and the flue sheet. It is formed upon its rear end to interlock with the bricks a and thus be held from falling, the weight of the arch when completed holding it firmly against the flue sheet. I next arrange a second span above the first span, upon the tubes, and hold it in position by placing the roof or cover bricks b between the spans. The ribs b^2 on the cover bricks are deep enough so that the lower cover bricks contact with the tubes 9 and this prevents the cover bricks from sliding down out of their proper position. Should it be desirable, further spans and cover bricks may be placed in position to build an arch of the desired length or height. Having thus formed the main part of the arch I then place the side bricks c in position at the ends of the span bricks and between these I place further side bricks resting their inner ends upon the outer edges of the lower cover bricks. The tongue c' of the side bricks rests upon the upper surfaces of the cover bricks and thus holds the inner ends of the side bricks in position. This form of arch, being spaced from the flue sheet by the block d , provides openings 11 between the lower end of the arch and the flue sheet through which the ashes and cinders which collect upon the back or upper side of the arch are returned to the fuel bed.

A particularly valuable feature of the arch as herein described resides in the ease with which repairs to the side sheets or the side sheet stay bolts may be accomplished, as it is usually necessary to remove only the

light locking or side bricks c , when such repairs are necessary.

As many modifications of my invention will readily suggest themselves to one skilled in the art, I do not limit my invention to the specific structures herein shown and described.

Having thus described my invention, I claim as new and desire to secure by Letters Patent:

1. A locomotive boiler firebox equipped with two widely separated inclined arch-supporting tubes, in combination with a refractory arch supported by said tubes and held in spaced relation from the flue sheet, 80 said arch comprising a plurality of arched spans, each thereof composed of two bricks abutting substantially midway between the tubes and wedgingly resting thereon, and a plurality of roof bricks arranged between 85 the span bricks spacing them apart and closing the openings between them, means preventing lateral movement of the roof bricks on the span bricks, and comprising side bricks supported at their inner ends by the 90 span bricks and the roof bricks and at their outer ends wedgingly engaging the side sheets of the firebox, the inner ends of the side bricks and the outer edges of the arch being formed to provide coöperating substantially horizontal and vertical faces, as and for the purpose specified.

2. A locomotive boiler firebox in combination with two inclined arch supporting tubes therein arranged close to respective side sheets, a refractory arch body spanning from tube to tube and supported thereby, and inclined refractory leaves resting at their outer edges against respective side sheets and at their inner edges upon the 100 outer edges of the arch body, the outer edges of the arch body and the inner edges of the refractory leaves being formed with coöperating substantially horizontal and vertical faces, as and for the purpose specified.

3. A locomotive firebox comprising in combination, side walls, longitudinally inclined circulation tubes between said side walls, and a baffle wall on said tubes comprising intermediate brick resting upon the 115 circulation tubes, and side brick inclined in position and having their outer ends resting against the side walls, said intermediate and side bricks being provided with substantially horizontal and vertical coöperating faces, said faces being respectively so constructed and arranged as to cause the side brick to bear downwardly upon the intermediate brick and horizontally against the 120 same.

4. A locomotive boiler fire box and its side sheets in combination with longitudinally arranged circulation tubes therein, a refractory baffle extending from side sheet to side sheet supported by the tubes and comprising 130

- intermediate bricks resting on and supported by the tubes and side bricks in inclined position, their outer ends resting against the side sheets and their inner ends formed to 5 coöperate with the outer ends of the intermediate bricks and provided with substantially horizontal and vertical contacting faces, as and for the purpose specified.
5. A locomotive boiler fire box and its side 10 sheets in combination with longitudinally arranged circulating tubes therein, a refractory baffle wall on said tubes comprising intermediate bricks resting on and supported by said tubes, and provided with portions 15 depending between the tubes and side bricks inclined in position resting at their outer ends against the side sheets and their inner ends formed to provide faces supported upon the upper faces of the adjacent intermediate 20 bricks and other faces bearing against the end faces of the intermediate bricks, as and for the purpose specified.
6. A locomotive boiler fire box having longitudinally arranged arch tubes therein, in 25 combination with a refractory arch body supported by the tubes and comprising intermediate bricks resting at their ends upon the tubes and side bricks arranged in inclined position, their outer ends resting 30 against the side sheets and their inner ends resting on the outer ends of the adjacent intermediate bricks, the outer ends of the in-
- termmediate bricks being formed to present substantially horizontal and vertical faces for contact with the inner ends of the side 35 bricks, as and for the purpose specified.
7. A locomotive boiler fire box having arch tubes extending longitudinally therein, in combination with a refractory arch body extending from side sheet to side sheet 40 resting upon the tubes and comprising intermediate bricks resting at their ends upon the tubes and having parts depending between the tubes and provided at their outer ends with V-grooves in the upper edges 45 thereof, and side bricks resting at their outer ends against the side sheets and having their inner ends in said V-grooves, as and for the purpose specified.
8. A locomotive fire box provided with 50 arch tubes, in combination with a refractory arch body supported on said tubes and side bricks for engagement with the sides of the fire box and each formed with a V-groove 55 at its inner end, for complementary engagement with either edge of said arch body.

In testimony whereof, I have hereunto set my hand, this 5th day of December, 1911, in the presence of two subscribing witnesses.

CHARLES B. MOORE.
